(57) CLAIM

I claim the ornamental design for a body of vacuum cleaner, as shown and described.

DESCRIPTION

FIG. 1 is a perspective view of a body of vacuum cleaner showing the design;

FIG. 2 is a front view thereof;

FIG. 3 is a rear view thereof;

FIG. 4 is a left-side view thereof;

FIG. 5 is a right-side view thereof;

FIG. 6 is a top plan view thereof; and,

FIG. 7 is a bottom plan view thereof.
